Inventor:

Claudius Dornier.

UNITED STATES PATENT OFFICE.

CLAUDIUS DORNIER, OF FRIEDRICHSHAFEN, GERMANY, ASSIGNOR OF ONE-HALF TO
DORNIER-METALLBAUTEN, GESELLSCHAFT MIT BESCHRÄNKTER HAFTUNG, OF
FRIEDRICHSHAFEN, GERMANY.

FLYING BOAT.

Application filed June 28, 1920. Serial No. 392,562.

To all whom it may concern:

Be it known that I, CLAUDIUS DORNIER, a citizen of the German Empire, residing at Friedrichshafen, Germany, have invented 5 certain new and useful Improvements in Flying Boats (for which I have filed application in Germany, November 18, 1919), of which the following is a specification.

My invention refers to flying machines 10 and more especially to flying boats. Its particular object is an improved arrangement of the motor and the supporting planes relatively to the boat hull in special connection with craft having one or a plurality 15 of traction propellers.

Hitherto the type of hydroplanes, called flying boats, was almost unexceptionally provided with driving propellers and hence with raised motors, being generally constructed as a double deck aeroplane. A construction of this kind embodies manifold and serious disadvantages. Above all, the center of gravity of the craft is located 20 rather high, while the motors are only accessible with great difficulty.

The present invention aims at obviating these drawbacks, by the propeller being arranged at the bow, in such wise that the distance between the water and the circle described by the propeller will be as slight as 30 admissible. To this end, the propeller is either directly or indirectly driven by a motor or a motor plant, which is disposed close to the bow on low structures or immediately on the boat. A substantially self supporting wing is mounted immediately on the deck. However, if desired, the said wing may in addition be supported by means of struts directly connecting it with the boat, 40 or by aid of side floats. A construction of the kind described will go to form a boat having a very favorable low lying total center of gravity and hence possessing great stability both in the air as also on the water. 45 Beyond this, the resistance to the air is, in the present case, considerably reduced in comparison to the known constructions, while the motors or the like, are rendered far more easily accessible than heretofore.

I wish it to be understood that my invention is by no means restricted to flying boats and hydroplanes in general having but a single traction propeller. It may equally be adapted to craft provided with two floats and one traction propeller arranged on each 55 float, and the number of wings may likewise be varied without departing from the spirit of the invention. And though the invention has been described above as applied to a single deck hydroplane, additional supporting planes might be disposed over the first plane located in the deck of the craft.

A structure embodying the features of my invention is clearly illustrated in the accompanying drawing forming part of this specification. In the drawings—

Fig. 1 is a side elevation and

Fig. 2 is a plan.

The boat proper 1 is provided, close to its bow, with a motor 2 driving a traction propeller 3. The said propeller is disposed at so low a point as to almost touch the water level 4. The supporting plane 5 is situated directly on the deck, leaving a space 6 free for the driver between the motor and its front edge. The boat 1 is fitted out with lateral openings 7 in the shape of doors and windows, its end being provided in the customary manner with a rudder and fins 8.

I claim:—

A flying boat comprising in combination, a stepped float-less boat's hull, a motor disposed directly on the foremost part of said hull and a traction propeller adapted to be driven by said motor and extending, when in vertical position, almost down to the level of the load water line, a self supporting plane extending close to the rear of said motor across said hull in contact with its upper deck, a pilot's seat between said motor and said plane and accommodation for the variable load in said hull underneath said plane.

In testimony whereof I affix my signature.

CLAUDIUS DORNIER.
